MANHOLE CLOSURE

George E. Woods, Jr., New York, N. Y., assignor
to Consolidated Gas Company of New York,
New York, N. Y., a corporation of New York

Application May 12, 1932, Serial No. 610,811

9 Claims. (Cl. 94—34)

This invention relates to manhole closures and the like and provides improvements therein.

When an explosion occurs in a manhole the cover, or covers where the manhole is provided 5 with an inner and an outer cover, are usually fractured and parts or fragments projected with dangerous force for a considerable distance from the manhole. In manholes having an inner and an outer cover experience and experiments show 10 that the fracturing, and consequent number of fragments, is considerably increased, many of the fragments being projected laterally in a low trajectory for a distance of several hundred feet. It has been found that these fragments are mostly 15 parts of the inner cover, and the lateral projection thereof I attribute to the fact that the inner cover is either initially shattered, or is projected forcibly against the underside of the stronger cover and shattered. The outer cover, even though it is itself driven upwardly by the 20 explosion, offers a resistance which forces the gases to spread laterally and carry with them the shattered parts of the inner cover.

The present invention provides a structure for 25 closing manholes comprising either a single cover, or an inner and outer cover, and means whereby the projection of the outer cover under the force of an explosion is reliably restrained and the cover reliably retracted to a position which will 30 cover or protect the manhole opening, without shattering and scattering of fractured parts, the inner cover, where one is used, being so constructed and arranged that it does not shatter, and is reliably retained within the cavity beneath the 35 outer cover.

An embodiment of the invention is illustrated in the accompanying drawing, wherein:

Figure 1 is a vertical sectional view through a manhole provided with a closure according to the 40 present invention, and showing the parts in normal closed position.

Fig. 2 is a similar view showing the closure parts in the maximum position to which they are driven by the force of an explosion.

Fig. 3 is a similar view showing the retracted position of the parts following an explosion.

Fig. 4 is a perspective view partly in vertical section, with the section at right angles to the sections shown in the preceding views.

Fig. 5 is a perspective view of a detail.

Fig. 6 is a view of a detail, showing in vertical section a portion of the inner cover with a packing interposed between the inner cover and the part of the hatch on which it seats.

Referring to said drawing, numeral 10 design-

nates a manhole, which may be formed as usual of masonry 12 with metal hatch 14 flush with the roadway and provided with a countersunk shoulder 16.

The manhole illustrated is of the type having an 5 outer cover 20 and an inner cover 22 (sometimes called a "pan"). The invention herein set forth may nevertheless be embodied in manholes having an outer or single cover, and the novel features pertaining to the inner cover may be employed independently of the novel features pertaining to the outer cover, and vice versa.

The cover 20 is preferably heavy and strong and in closed position fits with its edge on the shoulder 16, substantially flush with the roadway. 15

Numerical 25 designates yielding means for resisting the driving upward or projection of the cover 20 by the force of an explosion inside the manhole, and for retracting it to its closed or virtually closed position.

The means 25 preferably comprises a rod 26 attached to the center of the cover 20 and extending down into the manhole, and a spring 28 or equivalent restraining device. The spring 28 abuts or reacts against the lower part of the 25 rod 26, and for this purpose a washer 30 confined by a nut or nuts 32 threaded on rod 26, may be provided. A part 34 firmly secured to a fixed

part of the manhole 10 sustains the force or reaction of the upper end of spring 28 when the latter is compressed. The part 34 is preferably a bar extending diametrically across the manhole, having lugs at its ends adapted to fit into bayonet-joint sockets 36, which are usually provided on the inner sides of manhole hatches 14. 30

The bar 34 is made strong to resist deformation by stresses thereon incident to restraining the cover 20 following an explosion. The force and coaction of the spring 28, or other yielding means, is such that its elasticity is not exceeded by the 40

force acting against it due to the explosion, so that the spring or other means does not jam and produce a shock on the cover which, added to the strain already thereon, would have a strong tendency to cause the cover to break. The spring 45 is long and the modulus of elasticity of the spring such that a small force will cause a considerable compression. The result is that the outer cover

offers little initial resistance other than its own inertia to being raised. As soon as it has been 50 lifted a vent for the gases is at once provided without either rupturing shock or impact to any part of the device.

The rod 26 is preferably connected to the center of the cover 20, and guided in a central open- 55

ing 38 in the restraining bar 34. The strain on the cover 20 produced by the pull of the rod 26 against the force of an explosion is thereby nearly symmetrically distributed in the cover and liability to cracking very much diminished. Also by this arrangement it is possible to utilize the type of outer cover now generally in use without any change. In those cases where ventilating holes are not provided the existing covers can be used by merely drilling one hole in the center of them. Moreover, the pull of the cover on rod 26 is thereby made to act substantially in line with the axis of the manhole, and liability of the rod 26 to being bent and causing interference with the action of the spring to retract the cover to a position covering or virtually covering the manhole, avoided. Furthermore by this arrangement the yielding means can be utilized without attaching anything permanently to the manhole vault or altering it in any way, as the central unattached position of the rod is out of the way of ladders used for descending and is removed from the opening together with and as an integral part of the device.

25 The cover 20 may be detachably connected to the rod 26 by a cap-screw 40 having threaded connection with a nut or sleeve 42 on the upper end of rod 26. The cap-screw 40 may be provided with spanner-holes 44 (Fig. 4) for turning.

30 The cover 22 is of a form to resist shattering under the force of an explosion. For this purpose the cover 22 is preferably made of a sheet of ductile metal, such as ductile steel, capable of readily bending under the force of an explosion under the covers. Moreover, the cover 22 of ductile metal is preferably provided with means for directing the bending of the cover under the force of an explosion so that when the cover is fastened portions thereof may turn 35 up in the manner of flaps, as indicated at 50. A reinforcement or bar 55 across the top of cover 22, may be provided for directing the bending of cover 22, and such means are preferably arranged to extend diametrically in line with bar 40 34 when the latter is also employed. In a closure including both an inner cover 22 and an outer cover 20, the restraining construction heretofore described is preferably employed, and the bar 34 may be provided with means, as bolts 56, 45 adapted to bear on the inner cover 22 and fasten 50 and hold it against the shoulders 58 on the hatch 14. In the absence of other means, the underside of the bar 34 extending diametrically across the manhole and across the cover 22 would 55 act to direct the bending. The rod 26 would extend through the cover 22, and the upper end of spring 28 would bear on the underside of said cover 22, the bar 34 ultimately sustaining the force exerted through spring 28. When only an 60 outer cover is used the upper end of the yielding means will react against the underside of the retaining bar 34.

In many instances the inner covers of the manhole closures are arranged to seal the opening through the manhole for the purpose of making the space below the manhole watertight, etc. The cover 22 so arranged is illustrated in Fig. 6; a packing 60 is interposed between the shoulder 58 of the hatch 14 and the edge of the cover 22, 65 and the bolts 56 may be screwed down onto the cover 22 so as to compress the packing against shoulder 58 and provide a tight joint to thereby seal the opening. Preferably the cover 22 is provided with a channel or groove 62 in its per-

ipheral portion to receive or contain the packing 60 in the form of a washer or gasket.

The cover 20 may be of the "ventilated" type, or may be imperforate. In Fig. 4 the cover 20 is shown as provided with openings 66; in the other figures the cover 20 is shown without openings.

The inner cover 22 may also be of the "ventilated" type, or may be imperforate. In Fig. 4 the inner cover 22 is shown as provided with 10 openings 68, and in the other figures it is shown without openings.

Operation

When an explosion in a manhole occurs, the force will bend the inner cover, the bending being directed by the reinforcing web or bar 55 or other means, and the cover-parts or flaps 50 will open allowing gas to pass and avoiding shattering of the cover 22, especially when made of ductile metal. The fastening means (bar 34 and bolts 56 in the illustrated embodiment) will hold the cover 22 against being blown out of the manhole. The force of the explosion against the underside of cover 20 will lift it against the reaction of 25 the spring 28 or other restraining means. As soon as the outer cover (20) has opened, the initial force of the spring being slight, practically the only resistance that the outer cover will offer is its own inertia which is small enough 30 to prevent shattering from the initial shock and will permit it to rise. As soon as it has been raised off its seat a vent is at once provided which relieves the explosive force more and more as the opening widens until the reacting force due to 35 the spring which is becoming greater as the opening increases is able to overcome the explosive force which diminishes as the vent becomes larger. The outer cover will therefore come to rest without jar or shock before the spring has been 40 completely compressed and, when the force of the explosion has been spent, will be retracted to its original position. If the upwardly bent flaps 50 of the inner cover 22 project so high as to strike the underside of cover 20, the manhole 45 will be virtually covered, as illustrated in Fig. 3, so as to protect the opening against anyone falling in. Moreover the dangers consequent upon shattering and scattering of the shattered parts are avoided. No other consequence than deformation of the inner cover, which is readily replaceable, need follow a manhole explosion when 50 a manhole is provided with a closure according to the present invention.

The invention may receive other embodiments than that herein specifically illustrated and described.

What is claimed is:

1. A manhole closure consisting of an inner and an outer cover, the outer cover resting on its 60 seat at the outer surface of the manhole under normal conditions and being capable of rising under explosive forces, the inner cover being of flexible material and having means for retaining it substantially below the upper surface of 65 the manhole against bodily projection under explosive forces.

2. A manhole closure consisting of an inner and an outer cover, the outer cover resting on its seat at the outer surface of the manhole under normal 70 conditions and having means for yieldably restraining its upward projection under explosive forces, the inner cover being of flexible material to permit bending under the influence of explosive forces and means for retaining the inner cover 75

substantially below the upper surface of the manhole against bodily projection under such explosive forces.

3. A combination according to claim 2, wherein in said flexible inner cover is provided with means for guiding the bending thereof under the action of explosive forces.

4. A combination according to claim 2, wherein said means for yieldably restraining the upward projection of the outer cover is a rod attached to the outer cover and extending downwardly into the manhole and a spring positioned between an abutment on the rod and a fixed part in the man-

hole.

5. A combination according to claim 2, wherein said means for retaining said inner cover in the manhole is a retaining-bar extending above the inner cover across the manhole and engaging fixed parts in the manhole.

6. A combination according to claim 2, wherein said means for retaining said inner cover in the manhole is a retaining-bar extending above the inner cover across the manhole and engaging fixed parts in the manhole, and wherein said

means for yieldably restraining the upward projection of the outer cover is a rod attached to the outer cover and extending downwardly into the manhole and through said retaining-bar, and a spring positioned between an abutment on said rod and said retaining-bar, which latter acts as a fixed abutment.

7. A combination according to claim 2, wherein said means for retaining said inner cover in the manhole is a retaining-bar extending across the manhole and engaging fixed parts in the man-

hole, and wherein said flexible inner cover has a diametral reinforcement arranged to be alined with said retaining-bar and to guide the bending of the flexible inner cover under the action of explosive forces, and means on said retaining-bar for bearing on said diametral reinforcement to normally press said inner cover against its seat.

8. A closure for a manhole comprising an outer cover, restraining means attached to said outer cover and acting to yieldingly resist the projection of said cover by the force of an explosion, a yieldable inner cover, and means for fastening said inner cover, said inner cover being constructed and arranged to be held by said fastening means under the forces of an explosion and while so held to yield so as to readily pass gases driven outward by said force of explosion, said restraining means attached to said outer cover comprising a rod attached to said outer cover a spring acting on said rod, and a fixed abutment against which said spring acts.

9. A closure for a manhole comprising an outer cover, restraining means attached to said outer cover and acting to yieldingly resist the projection of said cover by the force of an explosion, a yieldable inner cover, a retaining-bar extending diametrically across said manhole and acting to fasten said inner cover, said inner cover having yieldable portions on each side of its diametrical portion which is alined with said retaining-bar, said restraining means attached to said outer cover comprising a rod attached to said outer cover, and a spring between said rod and said retaining-bar.
